UNITED STATES PATENT OFFICE.

FREDERICK W. DUFWA, OF MEXICO, MEXICO.

BLADE FOR PROPELLERS FOR AIR-SHIPS.

SPECIFICATION forming part of Letters Patent No. 694,356, dated March 4, 1902.

Application filed May 15, 1901. Serial No. 60,278. (Model.)

To all whom it may concern:

Be it known that I, FREDERICK W. DUFWA, a subject of the King of Sweden and Norway, residing at the city of Mexico, in the Republic of Mexico, have invented a new and useful Blade for Propellers for Air-Ships, of which the following is a specification.

5 My invention relates to an improvement in the construction of blades for propellers for air-ships.

10 The object of my improvement is to provide a means by which a ponderable object, such as the body of an air-ship, may be raised up into the air and maintained in position there 15 or when raised into the air may be propelled in a horizontal or other direction. I attain this object by the mechanism shown in the accompanying drawings, in which like letters refer to similar parts in all the figures.

20 The figures show two of my blades rigidly joined to a hub, by means of which they may be revolved.

25 Figure 1 is a side elevation of my device, showing two of my improved blades united to form a propeller. Fig. 2 is a plan or face view of the same. Fig. 3 is a cross-section on the line *x y* of Fig. 2.

30 *b* is the body of my blade and is constructed, preferably, in the bellied form shown in the drawings, although its faces may also be helicoids or plane surfaces or longitudinally concaved throughout.

35 *c* constitutes the taking edge of the blade and is formed of a strip of material substantially V-shaped or trough-like in cross-section, as shown in Fig. 3. It is attached to the body *b* in such a manner that its interior or concave side lies over against the upper or forward edge of the body *b*, leaving the space 40 *d*, as shown in Fig. 3. The portion of the strip *c* which is above the forward edge of the body *b* is preferably as nearly parallel to the plane of rotation as possible in order to offer the least possible resistance to the air. The 45 lower portion of the strip *c*, which lies beneath the forward edge of the body *b*, is preferably arranged to lie at an angle of about fifty-five degrees to the plane of rotation.

50 My blade may be constructed of any suitable material having both lightness and strength, such as aluminium, wood, pasteboard, celluloid, wire or ratan netting cov-

ered with canvas, &c. Any skilled mechanic will be able to determine what material is best suited for use under the circumstances. 55

One or more of my wings are attached to a hub *a* in such a manner that when the hub is rotated by means of a shaft in operative connection with some source of motive power carried by the air-ship the blades will revolve 60 in the direction of the arrows in Fig. 2—that is to say, the part *c* will always precede the part *b*. Of course other means may be employed for attaching my blades to the shaft. These are well known in the art and need not 65 be further specified.

The propeller, consisting of the hub or its equivalent and one or more of my improved blades, may be attached to an air-ship in the position and manner well known in the art. 70 If attached to the air-ship so that the blades may revolve in a substantially horizontal plane, the propeller if revolved with sufficient force and rapidity will raise the same into the air and maintain it in position there. If 75 attached to the air-ship in such a manner that the blades may revolve in a substantially vertical plane, the propeller will if revolved with sufficient force and rapidity propel the same in a substantially horizontal direction. Any 80 mechanic will be able to determine the size of the propeller to adapt the same to propel any given air-ship in a vertical or horizontal direction and the amount of force and speed which must be given to the rotation thereof. 85 When the blades are revolved as described, the part *c* will compress the air in front of it down under the part *b*. The compressed air rushing in beneath the part *b* expands there and raises the blades upward. The opening 90 *d* is provided to allow an escape of air in an upward direction and also lessens the upward resistance of the blade to the air. At least this is the only theory upon which I account for the satisfactory operation of my device. 95

In order to carry out my invention, neither the number of blades nor the exact construction of the same nor the manner of connecting the same with the source of motive power 100 is of any consequence as long as the substantial construction of my blade, especially the inclined part *b* and the wedge-shaped part *c*, substantially arranged as shown, is retained.

I wish it to be understood that in using the word "propeller" in my claims I intend to describe a device by means of which an air-ship or other analogous object may be moved or 5 propelled in the air in any direction whatsoever.

I claim—

1. The propeller-blade consisting of the body portion *b* and the trough-shaped strip *c*, 10 arranged to leave the opening *d* between them and united to and carried by a hub *a*, substantially as described.
2. The propeller-blade consisting of body *b* and V-shaped strip *c* united near their ends

but arranged to leave the opening *d* between 15 the body and the strip as specified.

3. A propeller for air-ships comprising a central hub or shaft, and a plurality of blades, each consisting of the curved body portion *b* and the V-shaped strip *c* forming opening *d* 20 between them, substantially as described.

In testimony whereof I have signed my name to this specification in the presence of two subscribing witnesses.

FREDERICK W. DUFWA.
